COMBINED PERFORATOR AND TRIMMER FOR PIE CRUSTS

Maude L. Butcher, Seattle, Wash.

Application July 5, 1949, Serial No. 3,701

Term of patent 7 years

(Cl. D44—29)

To all whom it may concern:

Be it known that Maude L. Butcher, a citizen of the United States, residing at Seattle, Washington, has invented a new, original, and ornamental Design for a Combined Perforator and Trimmer for Pie Crusts, of which the following is a specification, reference being had to the accompanying drawing, forming a part thereof, in which:

Figure 1 is an inverted perspective view of my combined perforator and trimmer for pie crusts;

Figure 2 is a view in side elevation of the device of Figure 1 in upright position; and

Figure 3 is an enlarged cross-sectional view taken on line 3—3 of Figure 1.

I claim:

The ornamental design for a combined perforator and trimmer for pie crusts, as shown.

MAUDE L. BUTCHER.
